(57) **CLAIM**

The ornamental design for an electrical alternator, as shown and described.

DESCRIPTION

FIG. 1 is a front view of an electrical alternator according to the present invention.

FIG. 2 is a rear view thereof.

FIG. 3 is a first side view thereof.

FIG. 4 is a second side view thereof.

FIG. 5 is a top view thereof.

FIG. 6 is a bottom view thereof.

FIG. 7 is a first isometric view thereof; and,

FIG. 8 is a second isometric view thereof.

The ornamental design which is claimed is shown in solid lines in the drawings. Any broken lines in the drawings are for illustrative purposes only and form no part of the claimed design.
